UNITED STATES PATENT OFFICE

2,046,953

BEVERAGE SHIPPING AND STORAGE CONTAINER

John L. Kellogg, Chicago, Ill., assignor to
Helen L. Kellogg, Chicago, Ill.

Application October 1, 1934, Serial No. 746,301

3 Claims. (Cl. 62—91.5)

This invention relates to improvements in the construction and design of containers which are particularly adapted for use in the handling of beer and other carbonated beverages which, when handled in bulk, must be maintained at a comparatively low temperature to avoid danger of fermentation and also to prevent separation of the carbonating gas from the beverage.

An important object of the invention is to provide a container for the purpose specified consisting of inner and outer receptacles which are separable from one another, the inner receptacle being usable, if desired as an independent unit and having a storage compartment formed therein for holding a supply of solidified gaseous refrigerant, the receptacles being so arranged that in the assembled position they are held completely out of contact with each other by an intervening layer of insulating material, whereby to reduce to an absolute minimum the tendency for transfer of heat to the walls of the inner receptacle.

Another object of the invention is to provide in combination with a double walled refrigerating container of the type specified, a cabinet which is designed to enclose the container and to serve as an additional means for preventing transmission of heat to the beverage during the period when the latter is being stored and dispensed at the retailing establishment.

Another object of the invention is to provide a beverage shipping and storage container having a refrigerant storage compartment formed therein and adapted to hold a supply of a solidified gaseous refrigerant, such as carbon dioxide, said compartment having valve means arranged to permit passage of gaseous refrigerant to the interior of the container, and additional valve means for permitting escape of gaseous refrigerant directly from said compartment into the atmosphere.

Another object of the invention is to provide a shipping and storage container having valve means for the purpose specified which is operable to maintain a pressure differential between the storage compartment and the interior of the container sufficient to expand the gas within the container at a rate which will prevent any extended drop in pressure therein after withdrawal of a portion of the beverage through a tap faucet.

A still further object of the invention is to provide a container having cooling means of the character set forth which is adapted to be used either as a complete and independent unit for the storage of the beverage or, if desired, in combination with an outer receptacle which is ar-

ranged to be completely isolated therefrom by means of an intervening layer of insulating material.

Other objects and advantages of the invention will be apparent from the following detailed description, taken in conjunction with the accompanying drawings, wherein I have shown the preferred form in which I have thus far contemplated applying the principles of the invention.

Referring to the drawings:

Fig. 1 is a broken elevational view showing the inner and outer receptacles arranged in assembled position, with the inner receptacle charged with a supply of refrigerant, the view also showing the assembled unit positioned in a storage cabinet which is designed for use with the unit at the retailing establishment;

Fig. 2 is a horizontal section through the container and associated storage cabinet, the view being taken substantially on line 2—2 of Fig. 1, portions of the top cover plate of the outer receptacle being broken away to show the construction of the top wall of the inner receptacle;

Fig. 3 is a plan view of a blanket of insulating material which is wrapped around the walls of the inner receptacle;

Fig. 4 is an elevational view of the inner receptacle;

Fig. 5 is an elevational view of the outer receptacle;

Fig. 6 is a perspective view of the layer or sheet of insulating material which is placed at the bottom of the inner receptacle; and

Fig. 7 is a perspective view of a similar sheet of insulating material which is placed between the top or upper end walls of the inner and outer receptacles.

Referring to the drawings in detail, the numeral 8 designates generally a barrel-shaped sheet metal receptacle which is adapted to serve as a shipping and storage container for a body of liquid such as beer, or the like, the receptacle consisting of a bottom head wall 11, a top head wall 12, and a cylindrical side wall 13 which are suitably welded together to form a liquid tight container. The side wall 13 is provided with a filling bung ring 14, which is closed by a bung 15, and the top head wall 12 is provided with a tap bushing 16 which is closed by a tap bung 17, said bushing being provided with an elongated tube or neck portion 18, the lower end of which is welded into head wall 12.

In accordance with one phase of my invention, I provide a refrigerant storage compartment for the container 8, which is arranged as an integral

part thereof, and which is adapted to hold a supply of a solidified gaseous refrigerant such as carbon dioxide, more commonly referred to as dry ice. To this end I provide adjacent the top head wall 12, an outer head wall 19, which is arranged in spaced relation to the wall 12, the perimetrical portion of the wall 19 being turned downwardly to lap side wall 13, as indicated at 21, the overlapping portion being welded to wall 13 to form a gas tight joint. The space 10 intervening between walls 12 and 19 serves as a refrigerant storage compartment in which blocks or cakes 22 of dry ice may be placed to provide for cooling of the interior of the receptacle 8 by a direct transfer of heat through the metallic walls thereof. As shown in Fig. 1 the outer head wall 19 is provided with an exteriorly threaded sleeve 23 which is closed by a cap 24, the latter being provided with an interiorly threaded flange portion 25, which is received on the outer end of sleeve 23. The central or web portion of cap 24 is provided with an outlet opening 26 which is closed by an escape valve, indicated generally by the numeral 27. The details of construction of this valve are not shown inasmuch as any desired type of gas valve may be used to control the escape of gas from the cooling compartment 10 through opening 26. A second valve means, indicated generally by the numeral 28, is provided in the wall 18 of tube 18 for controlling the passage of gaseous refrigerant from the cooling compartment 10 through opening 29 in the wall of said tube into the interior of the container. Any preferred form of gas operated valve may be employed for controlling this passage of gas from the cooling chamber into the interior of the receptacle. The supply of dry ice is introduced into the chamber 10 through sleeve 23, the latter being made sufficiently large to permit introduction of the blocks or cakes 22.

As best shown in Figs. 1 and 4, the receptacle 8 is barrel-shaped, being intended for use as a shipping and storage container for a carbonated beverage, such as beer, the supply of dry ice being introduced into the cooling chamber 10 as soon as the beer is kegged and made ready for shipment. After a container reaches the retailer it is placed in the vertical position shown in Fig. 1 and tapped through bushing 16, the draw-off or tap pipe (not shown) extending downwardly through sleeve 18 into the body of liquid 9. In accordance with one of the important features of the invention, the supply of dry ice is arranged to serve both as a cooling means and also as a means for providing gas pressure to force the beverage through the tap pipe which is inserted in the container. To this end valves 27 and 28 are arranged to automatically operate at such pressures as will maintain a pressure differential between the cooling compartment 10 and the interior of receptacle 8 sufficient to force the beverage from said receptacle as soon as the draw-off tap faucet is opened. For example, valve 27 would be adjusted to permit escape of gaseous refrigerant directly into the atmosphere as soon as the pressure reaches, say 40 pounds per square inch. With this setting of valve 27 it may be assumed that valve 28 would be adjusted to operate at say a pressure of 20 pounds per square inch. Valve 27, of course, serves as an escape valve when the pressure in the cooling chamber 10 becomes excessively high, and valve 28 provides the pressure adjustment between the said chamber 10 and the interior of the receptacle 8. Ordinarily,

therefore, valve 28 would be arranged to operate at a pressure somewhat above atmospheric pressure so as to insure effective forcing of the beverage from the container through the take-off pipe.

The relative adjustment of valves 27 and 28 will depend upon the size of the cooling chamber 10 as compared to the capacity of the container. In the embodiment shown the cooling chamber constitutes approximately one-twelfth of the volume of the complete receptacle, and for most commercial uses this would be about the relative size which would be most useful for the shipping of beer. It will be apparent that when the container 8 is practically full of beer the withdrawal of a small quantity of beer would produce a considerable drop in pressure in the space 31 above the liquid surface. However, as the space 31 increases the relative pressure drop therein upon the drawing off of a given amount of beer becomes less. Therefore, valves 27 and 28 should be adjusted to provide sufficient pressure difference between the cooling chamber 10 and the interior of the container to insure a rapid expansion of gas in the space 31 during the initial draw-off period when the container is substantially full. This will prevent anything more than a momentary drop in pressure within the container upon opening of the tap faucet, and avoids any need of waiting for the pressure to build up between successive draw-offs even when the container is practically full. This result, I find, is effectively accomplished with the arrangement of valves shown.

With further reference to Fig. 1, it will be noted that the cakes of dry ice 22 are wrapped in paper cartons or containers 32. These cartons are formed of porous paper of a soft, fibrous texture which will readily permit passage of carbon dioxide gas from the solidified mass. I find that the rate of evaporation of the dry ice may be effectively controlled by varying the amount or extent of wrapping of the blocks 22. If comparatively rapid evaporation is desired I employ a comparatively thin covering of paper, and by increasing the thickness of the wrapper, I am able to correspondingly decrease the rate of evaporation. The successful use of dry ice as a refrigerant depends largely upon employing a type of container which will conserve the supply of refrigerant without at the same time incurring the danger of freezing the contents of the container by the very low temperature obtainable with a refrigerant of this type. I find that both of these objectives are accomplished by employing a receptacle construction of the type shown and by wrapping the cakes of the ice before introducing them into the cooling chamber.

Although the inner receptacle 8 may be used as an independent unit, I prefer, in accordance with my invention to provide an outer receptacle 33 which is designed to receive the receptacle 8, with provision of means between the two receptacles for completely insulating them from one another. The outer receptacle, which is designated generally by the numeral 33, consists of a cylindrical side wall 34 which is closed at its lower end by a bottom plate or head wall 35. The upper end is closed by a removable cover plate 36 which is provided with openings 37 and 38 which register with tap bushing 16 and cap 24, respectively. The walls 34, 35 and 36 are made of sheet metal, and the side wall 34 is preferably reinforced with a pair of annular ribs 39. The upper and lower edges of wall 34 are curled outwardly to provide tube shaped reinforcing ribs 41 and 42. As

shown in Fig. 1 the brim portion of top wall 36 is curved upwardly to provide a curved flange 43 which rests upon rib 42. Flange 43, however, extends only partially around rib 42, thereby permitting wall 36 to be lifted from the container.

As shown in Fig. 1, the outer receptacle 33 is shaped to conform substantially to the contour of the inner receptacle 8 for the purpose of permitting insertion of an intervening layer of insulating material, the parts being so designed that this layer of material prevents any metallic contact between the two receptacles. To this end I provide around the lower portion of receptacle 8 a sheet metal sleeve 44 which may be welded at the point 45 to the side wall 13. A similar sleeve 46 is welded to the upper portion of wall 13. The lower edge of sleeve 44 is turned inwardly to provide a reinforcing rib 47 and a similar reinforcing rib 48 is provided around the upper edge of sleeve 46. If desired, the inner edge portions of these sleeves may be struck outwardly to provide reinforcing ribs 49. A reinforcing head wall or plate 51 is provided at the upper end of receptacle 8 adjacent the wall 19, the marginal portion of said plate 51 being welded to sleeve 46. An intervening sheet of insulating material 53 is preferably inserted between walls 19 and 51 to prevent excessive transmission of heat to wall 19.

30 The space between the side walls of receptacles 8 and 33 is filled with a body of insulating material 54, such as dry zero, or the like, which, as shown in Fig. 3, is made in the form of a blanket which may be wrapped around sleeves 44 and 46, 35 being secured in position by straps 55. The space between the lower head walls 11 and 35 is similarly filled with a packing of dry zero 56 which, as shown in Fig. 6, may be made in the form of a circular blanket of padding, which may be easily placed in position in the bottom of container 33. Another pad of insulating material 57 is employed to fill the space between the upper head walls 51 and 36, this pad, as shown in Fig. 7, being provided with suitable openings which register 40 with cap 24 and tap bushing 16. It will be apparent from Fig. 1 that with the upper and lower edge portions of blanket 54 extending well beyond the adjacent edges of sleeves 44 and 46, all metallic contact is avoided between the walls 50 of receptacle 8 and the adjacent walls of the outer receptacle 33. This arrangement effectively prevents transmission of heat to the inner receptacle and particularly to the refrigerant storage compartment 10 containing the blocks of dry ice 55 22. The insulating material, being in the form of a fabric lining, is easily arranged in position around the inner receptacle 8 when it is desired to use the latter in conjunction with receptacle 33.

As previously stated, top wall 36 of the outer receptacle 33 is made removable to permit the inner receptacle 8 to be inserted and withdrawn as desired. In the embodiment shown, after the head wall 36 is placed in the position shown in Fig. 1, it is locked to the receptacle by means of an expandable clamp ring 58 which extends around the upper brim portion 42 of receptacle 33 and partially overlaps flange 43 which forms a part of top wall 36. As shown in Figs. 2 and 5, this clamp ring is split at 59, one end thereof being provided with a bolt 61 which has pin and slot connection through a link 62 with the other end of the ring. A clamp lever 63, pivoted at 64 to link 62, and connected at one end to ring 58 by an arm 65, which extends through the slot in link 62, is provided for drawing together the ad-

jacent ends of said ring 58 to lock the same over rib 42 and flange 43. The position of the parts in the locked position is best shown in Fig. 2.

The receptacles 8 and 33 in the assembled position shown in Fig. 1 may be conveniently used as a shipping and storage container for malt beverages, the packing of insulating material which fills the space between the walls serving to effectively prevent undue evaporation of the dry ice. When the container has reached the retailing establishment, it may be tapped through bung 17 and the contents of the container drawn off as desired. During the period when the beverage is being dispensed the gaseous refrigerant passes through the valve means 28 to the interior of 15 the container in such regulated amounts as to insure a pressure on the interior of the container sufficient to force the beverage through the draw-off pipe. If at any time, either during the period of shipment or storage at the retailing establishment, the gas pressure in the cooling chamber becomes excessive it will automatically be relieved through valve 21. If it is desired to replace or add to the supply of refrigerant it is merely necessary to remove cap 24, and introduce 20 additional cubes of refrigerant into the cooling chamber.

In some cases it may be desirable to provide at the retailing establishment a cabinet into which the cooling unit may be introduced during the 30 period when the beverage is being dispensed. A cabinet which may be conveniently used for this purpose is shown in Figs. 1 and 2, and consists of a base 66, side walls 67, a back wall 68, and a front wall 69. The base and side walls are 35 preferably made of wood, the latter being joined at their edges by metal strips 71, and the front wall 69 being made removable to facilitate removal of the container unit, and also to permit operation of locking clamp 63. The top 40 wall or cover 72 of the cabinet is made of wood, or other suitable insulating material, and is provided with openings 73 and 74 which register with the corresponding openings in head wall 36. In the embodiment shown head wall 36 is secured by screws 75 to the under face of cover 72, and the latter, in turn, is locked in position by a lock 76. The cabinet thus serves not only as a storage cabinet for the beverage 50 container, but also tends to conserve the supply of dry ice used for cooling by preventing access of heat to the container 33. It is, however, intended as an auxiliary unit for use at the retailing establishment and would not ordinarily be used as a shipping container inasmuch as the 55 combined receptacles 8 and 33 in themselves serve as a complete shipping and cooling unit. If desired, casters or rollers 77 may be provided on the base 66 to permit the unit to be easily moved.

The foregoing detailed description has been given for clearness of understanding only, and no unnecessary limitations should be understood therefrom, but the appended claims should be 60 construed as broadly as permissible in view of the prior art.

What I regard as new and desire to secure by Letters Patent is:

1. A beverage storage and dispensing container 70 comprising a barrel-shaped receptacle having a double wall at one end thereof, providing a storage compartment for holding a supply of a solidified gaseous refrigerant, the outer wall thereof having an opening through which the refrigerant 75

- may be introduced, closure means for said opening, valve means in said compartment for automatically permitting escape of gaseous refrigerant to the atmosphere, and means comprising a 5 tap bushing positioned in said outer wall and having an elongated tubular body extending through the compartment to the inner wall for receiving the draw-off member of a tap mechanism.
2. A beverage storage and dispensing container 10 comprising a barrel-shaped receptacle having a double wall at one end thereof, providing a storage compartment for holding a supply of a solidified gaseous refrigerant, the outer wall thereof having an opening through which the 15 refrigerant may be introduced, closure means for said opening, valve means in said compartment arranged to automatically permit passage of gaseous refrigerant to the interior of the container upon falling of the pressure therein below a pre- 20 determined point, and means comprising a tap bushing positioned in said outer wall and having an elongated tubular body extending through

the compartment to the inner wall for receiving the draw-off member of a tap mechanism.

3. A storage and dispensing unit for malt beverages and the like comprising an inner sheet metal receptacle having a double wall over a 5 portion thereof providing a storage compartment for holding a supply of a solidified gaseous refrigerant, removable closure means positioned in the outer wall of said compartment permitting introduction of the refrigerant therein, an outer 10 sheet metal receptacle independent of and separable from said inner receptacle, said outer receptacle having a removable wall adjacent the outer wall of said storage compartment, a body of insulating material disposed in the space between said receptacle walls, said receptacles being shaped to completely avoid metallic contact between said walls through the intervention of said body of insulating material, and an outer 15 cabinet for enclosing said storage unit. 20

JOHN L. KELLOGG.
